US00D889567S

(12) **United States Design Patent** (10) **Patent No.:** **US D889,567 S**
Comfort (45) **Date of Patent:** **** Jul. 7, 2020**

(54) **TRACK CONFIGURATION**(71) Applicant: **Q-BA-MAZE Inc.**, Minneapolis, MN
(US)(72) Inventor: **Andrew Comfort**, Minneapolis, MN
(US)(73) Assignee: **Q-BA-MAZE Inc.**, Minneapolis, MN
(US)(***) Term: **15 Years**(21) Appl. No.: **29/588,772**(22) Filed: **Dec. 22, 2016**(51) LOC (12) Cl. **21-01**

(52) U.S. Cl.

USPC ..... **D21/565; D21/564**(58) **Field of Classification Search**USPC D21/340, 456, 567, 568, 564-565,

Primary Examiner — Manpreet S Matharu*Assistant Examiner* — Keith J Wilson(74) *Attorney, Agent, or Firm* — Padda Law Group(57) **CLAIM**

The ornamental design of the track configuration, as shown.

DESCRIPTION

FIG. 1 is a perspective view of a track configuration;

FIG. 2 is a front side view thererof;

FIG. 3 is a back side view thereof;

FIG. 4 is a top side view thereof;

FIG. 5 is a bottom side view thereof;

FIG. 6 is a left side view thereof; and,

FIG. 7 is a right side view thereof.

The broken lines shown in the drawings illustrate environmental subject matter and form no part of the claimed design.

1 Claim, 7 Drawing Sheets# US D889,567 S
